UNITED STATES PATENT OFFICE.

HENRY E. ZIPLINSKY, OF LANCASTER, PENNSYLVANIA.

RECEPTACLE.

Application filed October 29, 1920. Serial No. 420,454.

To all whom it may concern:

Be it known that I, HENRY E. ZIPLINSKY, citizen of the United States, residing at Lancaster, in the county of Lancaster and State of Pennsylvania, have invented certain new and useful Improvements in Receptacles, of which the following is a specification.

This invention relates to receptacles especially adapted for containing small articles such as parts of watches and the like.

In the receptacles now in use for containing small watch parts and the like, the cover is frictionally held in place and is difficult to remove when it is desired to gain access to the parts within the receptacle. Owing to the smallness of the receptacle, it is difficult to grip the cover thereof and when the cover is finally removed, the parts contained within the receptacle are, in a great many cases, spilled.

Therefore, an important object of this invention is to provide a receptacle especially adapted for containing small articles and having simple means whereby the articles may be removed without the necessity of detaching the cover.

A further object of the invention is to provide a receptacle of the class described which is neat in appearance, efficient in use, and cheap to manufacture.

Other objects and advantages of the invention will be apparent during the course of the following description.

In the accompanying drawing forming a part of this application and in which like numerals are employed to designate like parts throughout the same:

Figure 1 is a perspective view of a square box or receptacle embodying the invention.

Figure 2 is a perspective view of a round box or receptacle embodying the invention,

Figure 3 is also a perspective view of a hexagonal box or receptacle embodying the invention,

Figure 4 is a perspective view of a round box embodying the invention, the cover of the box being shown with a hexagonal opening,

Figure 5 is a vertical transverse sectional view through the receptacle illustrated in Figure 4,

Figure 6 is a vertical transverse sectional view through a slightly modified form of receptacle.

In the drawing, wherein for the purpose

of illustration are shown several preferred embodiments of the invention, the numeral 5 generally designates a receptacle which is adapted for the reception of small articles such as parts of watches. The box 5 is preferably of metal and is provided with a metallic cover 6 formed with flanges 7 which engage the side walls 9 of the box when the cover is applied. Owing to the smallness of the box it is difficult in a great many cases, to remove the cover 6 without spilling some of the parts contained within the box and, therefore, I have provided the top 6 with a round opening 10 through which the parts may be removed by means of small implements such as suitable tweezers. It will be observed that the opening 10 is disposed adjacent one end of the box so that when only a few parts are left in the box, the same may be readily removed by tilting the box and inserting the tweezers into the lower end of the box and gripping the parts.

In the form of the invention illustrated in Figure 2, the receptacle is designated by the numeral 12 and is round. A disc-like cover 14 is applied to the receptacle and is provided with a depending annular flange 16 which frictionally engages the side of the receptacle. In this case also, the top or cover 14 is provided with an opening 17 which is arranged at one side of the center of the box so that all of the parts contained within the box may be removed.

In the form of the invention illustrated in Figure 3, the box, which is designated by the numeral 18, is of hexagonal formation and is provided with upstanding side walls 20 which are engaged by depending flanges 22 formed along the edges of a hexagonal cover 24. The cover 24 is provided with a hexagonal opening 26 by means of which the contents of the box may be singly removed. The opening 26 in the top of the box is spaced from the center of the box.

As illustrated in Figure 4 of the drawing, the round cover 14 of the box 12 may be provided with a hexagonal opening 30 through which the contents of the box may be removed. Of course, the opening in the cover of the box may be square or any other desired shape without departing from the spirit of the invention.

With reference to Figure 6 of the drawing, it will be observed that the opening in the cover of the box may be surrounded by

a plurality of radial fins 32 which act to secure the contents of the box in position.

With reference to the foregoing description, taken in connection with the accompanying drawing, it will be observed that when it is desired to remove the contents of the box, it is not necessary to remove the top, since access may be readily had to the interior of the box through the opening in 10 the cover of the same.

Having thus described the invention, what is claimed as new is:

A receptacle for temporarily containing small mechanical parts comprising a shallow 15 body, a freely removable cover therefor, the

cover being provided with an opening there-through relatively close to its periphery and the adjacent side wall of the body whereby tilting of the receptacle toward the side at which the opening is located will cause the 20 contents of the receptacle to shift to a position in proximity to the opening to provide for their ready removal through the opening, and means on the under side of the cover to prevent crowding of the contents 25 under the opening when the receptacle is tilted.

In testimony whereof I affix my signature.

HENRY E. ZIPLINSKY. [L. s.]
